UNITED STATES PATENT OFFICE.

WILLIAM L. MITCHELL, OF BROOKLYN, NEW YORK, ASSIGNOR TO BATTLE CREEK SURGICAL SUPPLY & SUPPORTER CORPORATION, OF BATTLE CREEK, MICHIGAN, A CORPORATION OF MICHIGAN.

EXTENSIBLE ROD.

Application filed September 17, 1926. Serial No. 136,049.

This invention relates to improvements in extensible rods, and has for one of its objects to provide a simple and practical construction wherein a plurality of sections are 5 telescopically arranged and joined to each other in such manner that the same may be extended to secure a maximum length of rod.

Another object is to limit the movements 10 of the sections of the rod to extended positions by providing an intermediate section with a tube-like member having flanges at each end which contact the abutments carried by the adjacent sections so as to prevent 15 further outward movement of the sections relative to each other after the same have been fully extended.

The above and other objects will appear 20 more clearly from the following detail description, when taken in connection with the accompanying drawing, which illustrates a preferred embodiment of the inventive idea.

In the drawing—

Figure 1 is a longitudinal section through 25 a rod in extended position and constructed in accordance with the invention;

Figure 2 is a section on the line 2—2 of Figure 1; and

Figure 3 is a section on the line 3—3 of 30 Figure 1.

Referring more particularly to the accompanying drawing, the numerals 4, 5 and 6 indicate an intermediate and two end sections comprising the rod, the section 4 35 being telescoped within the section 5 while the section 6 is similarly arranged within the section 4.

The section 4 is provided with a closed 40 end 7 having an opening 8 which is surrounded by one end of a tubular member 9 arranged centrally within the section and extending longitudinally thereof for practically its entire length. The disposition of the member 9 with respect to the opening 45 8 forms on the closed end 7 an annular flange 10 which surrounds said opening. The opposite end of the member 9 is provided with an annular outturned flange 11 for a purpose which will presently appear.

The section 5 is provided with the closed 50 end 12 in which is centrally mounted one

end of a rod 13 extending longitudinally of the section and having its outer end projecting through the opening 8 in the section 4. Said outer end of the rod is provided with 55 a disk-like head 14 which forms an abutment movable in the member 9 and adapted to contact the flange 10 in order to limit the movement of the sections 4 and 5 to their extended positions and thereby prevent 60 complete detachment of said sections.

The section 6, which is movable within the section 4, surrounds the tubular member 9 and is provided at its inner end with an inturned flange 15 which is adapted to 65 contact the flange 11 at the outer end of the member 9 when the section 6 is at the limit of its extended position.

Thus the invention provides an extensible 70 rod which may be used for various purposes and in which the sections thereof may be extended to secure a maximum length for the rod and which, when in extended position, will be properly braced by the adjacent section and prevented from becoming accidentally detached therefrom.

What is claimed is:

1. In an extensible rod, an intermediate section having a tubular member forming an integral part thereof and extending from 80 one end of the section to a point adjacent its opposite end in spaced relation to the wall of said section, a second section into which the first named section telescopes, a rod in said second section projecting 85 through the first named end of said intermediate section and into said tubular member, said rod having means engageable with said first named end to limit outward movement of said intermediate section relative to 90 said second section, and a third section telescoped within said intermediate section, said third section and tubular member having cooperating means to limit the outward movement of said third section relative to 95 the intermediate section.

2. In an extensible rod, a plurality of tubular telescoping sections one of which is provided at one end with an inturned flange having an opening, said section also 100 having a tubular member surrounding said opening and extending from said end of

the section toward the opposite end in spaced concentric relation to said section and provided at said opposite end with an abutment, a rod carried by another of said sections and projecting through said opening and having a head movable in said tubular member for contact with said inturned flange to limit the movements of said sections to extended position, and a third sec-

tion within the first named section and having an abutment at its inner end cooperating with the abutment on said opposite end of the tubular member to limit outward movement of said third section. 10

In testimony whereof I have affixed my 15 signature.

WILLIAM L. MITCHELL.
